UNITED STATES PATENT OFFICE.

LEOPOLD OXHANDLER, OF CHICAGO, ILLINOIS.

SHIPPING CONTAINER FOR EGGS AND OTHER ARTICLES.

Application filed September 2, 1921. Serial No. 497,941.

To all whom it may concern:

Be it known that I, LEOPOLD OXHANDLER, a citizen of Russia, who has declared his intention of becoming a citizen of the United States, residing at Chicago, county of Cook, State of Illinois, have invented a certain new and useful Improvement in Shipping Containers for Eggs and Other Articles, and declare the following to be a full, clear, and exact description of the same, such as will enable others skilled in the art to which it pertains to make and use the same, reference being had to the accompanying drawings, which form a part of this specification.

My invention has for its object to produce a simple, light and strong container for eggs or other fragile articles which will permit the latter to be handled and shipped without danger of breakage, even though subjected to comparatively rough usage.

In my prior application Serial No. 476,778, dated June 11, 1921, I have disclosed a novel form of container built up of thick slabs filled with holes each large enough to receive an egg or other article. The slabs possess great mechanical strength and therefore not only protect the articles packed therein, but may be used over and over again without danger of breakage or distortion of the container. In one of its aspects my invention may be regarded as comprising an improvement on the aforesaid container, the slab-like form of the individual unit being retained, but the weight being reduced by a novel method of construction which also permits a different process of manufacture to be employed.

Generally stated, my present invention may be regarded as comprising a slab made up of any desired number of short open-ended tubes fastened together into a single unit; the size of the unit depending upon whether it be desired to ship eggs, for example, in quantities of a dozen or in lots containing several or many dozens.

The various features of novelty whereby my invention is characterized will herein-after be pointed out with particularity in the claims; but, for a full understanding of my invention and of its objects and advantages, reference may be had to the following detailed description taken in connection with the accompanying drawing, wherein:

Figure 1 is a plan view of one of my im-

proved slabs adapted to receive three dozen eggs;

Fig. 2 is a section on an enlarged scale taken approximately on line 2-2 of Fig. 1; 60

Fig. 3 is an edge view or side elevation of two of my improved slabs superposed upon each other and having so-called "flats" associated therewith, according to the method employed in packing a crate containing a plurality of slabs; 65

Fig. 4 is a plan view of a modified form of slab;

Fig. 5 is a section on an enlarged scale taken approximately on line 5-5 of Fig. 4; 70

Fig. 6 is a plan view of a fragment of a still further modification, parts being broken away more clearly to show underlying parts; and

Fig. 7 is a section on an enlarged scale 75 taken approximately on line 7-7 of Fig. 6.

Referring to Figs. 1, 2 and 3, 1 and 2 represent two flat sheets, preferably of cardboard or pulp, the member 1 having a series of tubes 3 projecting from one face thereof, 80 and the member 2 having a series of tubes 4 projecting from one of its faces. One set of tubes is made somewhat smaller in diameter than the other so that they may be telescoped upon each other. Thus, as shown in 85 Fig. 2, the tubes 3 slip into the tubes 4. This construction lends itself conveniently to a molding process, each sheet or plate with its tubular projections being molded independently of the other, and the two being then assembled; glue or other adhesive material being placed between the contacting surfaces of the two elements, if desired, in order permanently to connect them together. The tubes are open ended so that 95

when the two elements are assembled together they form in effect a thick slab through which extend openings each large enough to receive an egg. The number of openings, as heretofore stated, will depend 100 upon the number of eggs which are to be packed in a single container. If only a dozen eggs are to be packed, the parts will be so constructed that each slab will have a dozen egg-receiving openings or cells. The 105 most common method of packing eggs to be shipped in large quantities is to place them in layers of three dozen each and, for this use, each slab is preferably provided with thirty-six openings or cells, arranged in six 110 rows each containing six openings or cells. The usual flats are employed to close the

upper and lower ends of the opening or cells. Thus, in the arrangement shown in Fig. 3, the lowermost slab is placed upon a flat 5 and, after the eggs are packed into this slab another flat 5 is laid on top of the slab. The second slab is then placed upon a flat which overlies the first slab and, after the second slab has been filled with eggs, a third flat is placed on top of the same. This process is kept up until the desired number of eggs have been packed. It will be understood that any suitable crate or box may be used in conjunction with my invention.

If desired, the slabs may be built up out of individual tubes arranged in regular order in contact with each other and glued or cemented together if desired. Such an arrangement is shown in Figs. 4 and 5, the tubes 6 being, if desired, glued together along their lines of contact with each other and being bound into a single unit by means of a frame 7 of cardboard or other suitable material closely surrounding the same; the frame being of the same width or depth as the tubes and being glued or cemented thereto if desired.

For the sake of increased strength and rigidity, top or bottom, or both top and bottom cover plates may be attached to the unit shown in Figs. 4 and 5. Thus, as shown in Figs. 6 and 7, I have placed on top of the cellular slab a sheet or plate 8, preferably of cardboard or pulp, and provided with holes 9 equal in number to and registering with the tubes 6. A similar sheet or plate 10 is placed on the under side of the slab, this sheet or plate having holes 11 registering with the lower ends of the tubes. The members 8 and 10 are preferably glued or cemented upon the cellular structure so as to make a single rigid unit.

It will be seen that while the elements which go to make up the slab shown in Figs. 1 and 2 can best be made by molding them, the structures shown in Figs. 4 to 7 may be made out of simple tubing formed in continuous lengths by winding up strips of paper, the tubing being cut off into short lengths. In other words, no special machinery is required for the manufacture of the slabs shown in Figs. 4 to 6.

It will thus be seen that I have produced a simple and novel cellular slab structure which not only can be made cheaply but which possesses great strength and rigidity, will afford ample protection to fragile contents packed in the same, and will withstand rough usage so that it may be used over and over again.

While I have illustrated and described with particularity only a few preferred forms of my invention, I do not desire to be limited to the exact structural details thus illustrated and described; but intend to cover all forms and arrangements which come within the terms employed in the definitions of my invention constituting the appended claims.

I claim:

1. A container in the form of a slab made up of two parallel sheets or plates spaced apart from each other, a plurality of short tubes grouped in contact with each other, the tubes extending between said plates and connecting them together, said plates having openings registering with the ends of said tubes.

2. A container made of parallel sheets or plates of fibrous material spaced apart from each other and united by means of short parallel tubes of fibrous material grouped in contact with each other, said plates or sheets having openings therein registering with the ends of the tubes.

3. A cellular slab made up of a group of short tubes or fibrous material arranged with their axes parallel to each other and sheets of fibrous material extending across the ends of said tubes and permanently fastened thereto, said sheets having openings registering with the ends of said tubes.

4. A cellular slab made up of a group of short tubes of fibrous material arranged with their axes parallel to each other, sheets of fibrous material extending across the ends of said tubes and permanently fastening them together, said sheets having openings registering with the ends of said tubes, and a frame-like strip of fibrous material surrounding and secured to said group of tubes.

In testimony whereof, I sign this specification.

LEOPOLD OXHANDLER.
